UNITED STATES PATENT OFFICE.

JOSEPH PETERS, OF CHICAGO, ILLINOIS, ASSIGNOR OF ONE-FOURTH TO
PETER FOGELBERG, OF CHICAGO, ILLINOIS.

FIRE-ESCAPE.

SPECIFICATION forming part of Letters Patent No. 787,394, dated April 18, 1905.

Application filed June 30, 1904. Serial No. 214,740.

To all whom it may concern:

Be it known that I, JOSEPH PETERS, a citizen of the United States, residing at Chicago, in the county of Cook and State of Illinois, have 5 invented new and useful Improvements in Fire-Escapes, of which the following is a specification.

This invention relates particularly to that class of fire-escapes in which a rope is wound 10 upon a drum contained in a casing secured when in use to the person of the user, the upper end of the rope being attached to the window-ledge or other support. A brake operated by centrifugal force is provided to regulate the speed of the descent.

The invention is characterized particularly by improvements with respect to the brake mechanism and with respect to other details of construction, as will more fully hereinafter 15 appear.

In the accompanying drawings, Figure 1 is a perspective view illustrating the manner of use of the device. Fig. 2 is a front elevation, the front of the casing being removed. Fig. 5 is a central vertical section. Fig. 4 is a plan view showing the pawl and ratchet on the winding-drum. Fig. 5 is a detail in plan of the rope-guide which causes the rope to wind evenly on the drum. Fig. 6 is a detail in perspective of a roller which bears upon the drum and causes the rope to wind smoothly and tightly thereon. Fig. 7 is a detail of the brake mechanism. Fig. 8 is a detail in perspective, showing the brake-shoe.

Referring specifically to the drawings, 6 indicates the casing of the device, preferably formed of tin or light sheet metal, and 7 indicates a waistband by which the sleeve is secured to the body of the user. A stout metal frame 8 within the body of the casing supports the operative parts, and to the lower end of this frame are attached ropes 9, having at the end loops 10 to receive the feet of the user. This construction permits the hands of 15 the user to be free for other purposes. The running-rope 11, preferably made of wire, extends through an opening in the top of the casing and winds upon a drum 12, the axle 13 of which is properly supported in a frame. At the front end the axle has a rewinding- 50 crank 14 and a worm 15, and at the rear end the axle carries loose thereon a spur-gear 16, carrying a ratchet-wheel 17. This ratchet is engaged by pawls 18, fixed to the drum. The pawls slip when the rope is rewound on the 55 drum, so as to not operate the brake mechanism. At the top of the frame are rods 19, extending between the front and back pieces of the frame, and on these rods slide a guide-block 20, through an opening in which the 60 rope 11 runs. Directly under the opening is an antifriction-roller 21 to prevent binding of the rope in the opening. A pin 22 projects from the block 20 and into a cam-groove 23 in the roller 24, the shaft of which carries a 65 bevel-gear 25, in mesh with the bevel-gear 26 on the shaft 27, which is carried in suitable brackets 28, fixed to the frame, and has at its lower end a spur-pinion 29, meshing with the worm 15 on the drum-shaft 13. When the 70 rope is rewound, the cam-roller causes the block 20 to move back and forth along the rods 19, laying the rope in even layers around the drum, and when the apparatus is in use the same device causes the rope to pay out 75 smoothly and freely without danger of knots or kinks to stop the escape. The action is also assisted by a roller 30, which is carried by a bracket 31, pivoted upon a bolt 32, secured to the frame. The bracket is so arranged that it extends between the flanges of the drum and bears upon the rope-coil thereon under pressure of a spring 33, connected between the bracket and the frame. The roller 30 bears tightly against the rope and insures a close and even wind of the rope upon the drum, preventing looping and tangles generally.

The spur-wheel 16 is in mesh with a pinion 34 on a stud 35, projecting from the frame, 80 and said pinion is secured to a spur-gear 36, which in turn is in mesh with a pinion 37 on the shaft 38 of the centrifugal brake.

39 indicates a friction-ring securely fixed to the frame, and arranged to gear upon the 85 inner face of this ring is a pair of brake-shoes 40, pivoted to brackets 41, projecting from a sleeve 42, fixed upon the shaft 38.

43 indicates arms which are pivoted at 44 to the brackets 41 at right angles to the axis of the brake-shaft. One end of each of these arms carries a weight 45, and the other end 5 is hooked, as at 46, over a cam-surface 47 at the end of a piece 48, which forms part of the lever, the front end of which carries the brake-shoe 40. The sections 48 and 49 of this lever or device are pivoted together at 50 and 10 are normally held in straight position by a spring 51, connected to studs 52 on said parts. The rotation of the brake-shaft is effected by the gear-wheels above described, and the effect thereof is to cause the weighted arms to 15 tend to assume a straight position at right angles to the axis of the shaft 38. The movement of the arms causes the hooks 46 to bear down or in upon the cam-surfaces 47, which has the effect of turning the levers 48 and 20 49 upon the pivots 53, forcing the shoes 40 against the ring 39. When the desired limit of pressure is reached, the spring 51 yields, so that no greater pressure is applied except as such may be due to increased tension under 25 the influence of the weighted arms, and it will be understood that the spring 51 is of proper strength to insure an easy descent for a person of average weight. The gearing between the drum-shaft 13 and the brake-shaft 38 is such 30 that the speed is greatly multiplied. Consequently slight pressure of the brake-shoes 40 is sufficient to produce the action desired. Should the person be so light that the descent is too slow, it can be accelerated by turning

the crank 14, or should the person be so heavy 35 that the speed is too great it can be retarded by holding back on the crank 14, or the same effects may be effected by pulling one way or the other on the rope 11. As will be observed, the hands of the user are free for either of 40 these purposes.

The rope-winding mechanism above described prevents the rope from becoming accidentally unwound even when wire rope is used and in connection with the brake apparatus insures a device which will be ready and capable of efficient action when required. 45

What I claim as new, and desire to secure by Letters Patent, is—

In a fire-escape, the combination with a 50 drum and a rope wound thereon, of a brake-shaft geared to the drum, a fixed friction-ring extending around the shaft, brake-levers carried by the shaft and having at one end shoes arranged to contact with the ring, and having 55 cam-faces at the other end, brackets extending from the shaft and weighted levers pivoted upon said brackets at right angles to the brake-levers and having projections bearing upon said faces, as and for the purpose de² 6c scribed.

In testimony whereof I have signed my name to this specification in the presence of two subscribing witnesses.

JOSEPH PETERS.
